UNITED STATES PATENT OFFICE.

ARTHUR F. PITKIN, OF SCHENECTADY, NEW YORK.

STAY BOLT FOR STEAM BOILERS.

Application filed February 6, 1923. Serial No. 617,200.

To all whom it may concern:

Be it known that I, ARTHUR F. PITKIN, a citizen of the United States, of Schenectady, in the county of Schenectady and State of 5 New York, have invented a certain new and useful Improvement in Stay Bolts for Steam Boilers, of which improvement the following is a specification.

My invention relates to stay bolts for connecting, and resisting outward pressure upon, the inner and outer sheets of steam boilers, of the general class or type set forth in Letters Patent of the United States No. 1,432,085, granted and issued to me under 10 date of October 17, 1922. The object of my present invention is to provide improved means for connecting the plug of the stay bolt structure to a boiler sheet.

The improvement claimed is hereinafter 15 fully set forth.

In the accompanying drawing: Fig. 1 is a view, half in elevation, and half in axial section, of so much of a stay bolt structure as illustrates an embodiment of my invention; and, Fig. 2 an axial section showing a 20 modification of structural detail.

In the practice of my invention, referring descriptively to the specific embodiment thereof which is herein exemplified, the plug, 25 2, by which the stay bolt structure is connected to an outer sheet, A, of a firebox, instead of being made solid, as in prior practice, is recessed or relieved, either partially, as shown in Fig. 1, or entirely, as shown in 30 Fig. 2, thereby being in the form of a shell or case, of annular transverse section throughout, and having a wall of such thickness as will safely sustain the strain to which it is exposed in service, while being sufficiently thin to be expanded by the application of 35 internal pressure by a proper tool.

The upper end portion of the plug may be 40 of either frusto-conical or cylindrical form, and it is connected to the outer firebox 45 sheet, A, by being fitted in a hole of corresponding section, drilled in the sheet, and

firmly secured therein by expanding its wall, by a suitable expanding tool, so as to form a plurality of swells or projections, 2^d, on its periphery, which abut against the inner or 50 outer side of the sheet, A, or both. The projections which bear on the outer side of the sheet, are turned down thereon, and the plug may, if desired, be additionally secured by welding, the welding material 3, being applied around the projections on its outer end. 55

A tell tale hole, 2^c, in the neck, 2^b, of the plug, and a ball, 2^a, integral therewith, to which the body, 1, of the stay bolt, is articulated, are shown in Fig. 1, and Fig. 2 shows 60 a separate ball, 2^{aa}, around which the wall of the plug is pressed, the body of the stay bolt being articulated to the portion of the wall which surrounds the ball.

I claim as my invention and desire to secure by Letters Patent:

1. In a stay bolt structure, the combination of a bolt, having a socketed head; and a sheet plug articulated thereto, said plug having an annular wall, on which there is 70 formed a plurality of peripheral swells or projections, adapted to bear against the sides of a boiler sheet.

2. In a stay bolt structure, the combination of a bolt, having a socketed head; a 75 sheet plug, articulated thereto, said plug having an annular wall, on which there is formed a plurality of peripheral swells or projections, adapted to bear against a boiler sheet; and welding material connecting the 80 outer end of said plug to a boiler sheet.

3. In a stay bolt structure, the combination of a bolt, having a socketed head; a ball; and a sheet plug having a wall enclosing said ball, and articulated to said bolt, 85 and having a peripheral projection, adapted to bear against a boiler sheet.

ARTHUR F. PITKIN.
